CLAIM

We claim the ornamental design for a stool, as shown and described.

DESCRIPTION

FIG. 1 is a top perspective view of the first and second stool embodiments of the invention.

FIG. 2 is a bottom perspective view of the first embodiment of the invention.

FIG. 3 is a front elevation view of the first and second embodiments of the invention.

FIG. 4 is a back elevation view of the first and second embodiments of the invention.

FIG. 5 is a right side elevation view of the first and second embodiments of the invention.

FIG. 6 is a left side elevation view of the first and second embodiments of the invention.

FIG. 7 is a top plan view of the first, second and third stool embodiments of the invention.

FIG. 8 is a bottom plan view of the first embodiment of the invention.

FIG. 9 is a bottom perspective view of the second embodiment of the invention.

FIG. 10 is a bottom plan view of the second embodiment of the invention.

FIG. 11 is a top perspective view of the third embodiment of the invention.

FIG. 12 is a bottom perspective view of the third embodiment of the invention.

FIG. 13 is a front elevation view of the third embodiment of the invention.

FIG. 14 is a back elevation view of the third embodiment of the invention.

FIG. 15 is a right side elevation view of the third embodiment of the invention, the left side elevation view being a mirror image; and,

FIG. 16 is a bottom plan view of the third embodiment of the invention.

The dashed lines depict environment only that forms no part of the claimed design.
